TOBACCO PIPE

Filed Sept. 21, 1927

Fig. 3.

INVENTOR.

S. GUNNLAUGSSON

BY *Victor J. Evans*

ATTORNEY.

UNITED STATES PATENT OFFICE

SKULI GUNNLAUGSSON, OF RIO VISTA, CALIFORNIA

TOBACCO PIPE

Application filed September 21, 1927. Serial No. 221,029.

This invention relates to improvements in pipes and has particular reference to a tobacco pipe so constructed that it will readily prevent nicotine from reaching the mouth 5 of the user.

A further object of the invention is to equip the pipe with means that will serve to effectively collect and absorb within the pipe the products of combustion.

10 Another object of the invention is to provide in the pipe absorbent holding means, which absorbent can be quickly and conveniently replaced by a fresh piece of absorbent after the original absorbent has served its 15 purpose.

A further object is to provide a pipe of the character described which is economical to manufacture, comparatively simple in construction and highly efficient in use.

20 Other objects and advantages will be apparent during the course of the following description. In the accompanying drawings forming a part of this specification and in which like numerals are employed to designate like parts throughout the same—

Figure 1 is a longitudinal section through the pipe with the plug forming a part of my invention, being shown in elevation;

Figure 2 is a side elevation of the pipe 30 with a portion of the barrel being broken away, and

Figure 3 is a transverse vertical section through the barrel on the line 3—3 of Figure 2.

35 Great inconvenience has been experienced by pipe smokers due to the accumulation of nicotine and other juices in the pipe that often reach the mouth of the smoker. Furthermore when a pipe has been smoked for a considerable time the smoke often becomes heated with a resultant burning of the tongue of the smoker. The interior of the ordinary pipe is often difficult to clean due to the interior being inaccessible. To overcome these inconveniences I have provided means for readily absorbing the nicotine, means for cooling the pipe and means for permitting ready disassembly of the pipe so that access can be had thereto, and referring to the drawings

50 the numeral 4 designates the bowl of the

pipe provided with a chamber 5 that holds tobacco 6 therein. Integrally formed in the bowl is a barrel or tubular portion 7 having a chamber 8 communicating with the chamber 6 of the barrel through the medium of a passageway 9.

The numeral 10 designates a plug equipped with a sleeve 11 that is removably positioned in a bore 12 formed in the barrel. The plug 10 has connected thereto a rigid piece of wire 13 preferably made of aluminum, that extends through the sleeve 11 and continues through the length of the barrel 7. Slidably positioned on the wire 13 is a piece of absorbent 14 that conforms to the shape of the barrel 7 and has one of its ends retained within the sleeve 11. The opposite end of the absorbent contacts a cap 15 which has a plurality of spaced openings 16 formed therein. This cap is detachably secured as at 17 to a reduced portion 18 of a centrally bored stem 19 which in turn is removably secured to the barrel 7. The cap is also provided with a central opening 20 through which the wire 13 extends. The numeral 21 designates the conventional metal ferrule that is carried on the barrel for the purpose of enhancing the appearance of the pipe.

As a result of this construction when the tobacco in the pipe is lighted, the smoke being drawn therefrom will follow the course of the arrows illustrated in Figure 1, the drawing action of the smoker causing the smoke to pass through the passageway 9 thence through the openings 16 of the cap 15 and then through the bore of the stem 19 to the mouth of the smoker.

It will be evident that the moisture will collect on the absorbent 13 and nicotine will be prevented from reaching the mouth of the smoker, while the smoke entering the opening of the cap and passing through the cap will be readily cooled. It will be further observed that from the construction described, that the pipe due to its novel formation can be readily disassembled for cleaning purposes, and that when desired a new absorbent can be readily installed.

It is to be understood that the form of my invention herewith shown and described is

to be taken as a preferred example of the same and that various changes relative to the material, size, shape and arrangement of parts may be resorted to without departing from the spirit of the invention or the scope of the subjoined claims.

Having thus described my invention, I claim:

1. A tobacco pipe comprising a bowl, a tubular portion having a chamber formed therein and in communication with the bowl, a centrally bored stem detachably secured to one end of said tubular portion, a plug removably secured in the opposite end of said tubular portion, a wire secured to said plug and extending longitudinally of the tubular portion, an absorbent loosely mounted on said wire and secured at one end to said plug, and a perforated cap mounted on said stem and adapted to contact the free end of said absorbent.

2. A tobacco pipe comprising a bowl, a tubular portion having a chamber formed therein and in communication with the bowl, a centrally bored stem detachably secured to one end of said tubular portion, a plug positioned in the opposite end of said tubular portion, a sleeve connected to said plug, a rigid wire fixedly secured to said plug and extending through said tubular portion, an absorbent detachably secured to said wire and having one end thereof retained within said sleeve, and a cap member detachably secured to said stem and adapted to contact the opposite end of said absorbent, said cap member having openings therein communicating with the bore of said stem.

In testimony whereof I affix my signature.

SKÚLI GUNNLAUGSSON.
